UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

MACHINERY FOR CONVERTING SHEET MATERIAL INTO RECEPTACLES.

Application filed August 18, 1924. Serial No. 732,682.

This invention relates to machinery for making receptacles from paper or other sheet material, and particularly to machinery for making butter dishes, or similar receptacles, by automatically feeding and blanking the sheet material continuously, and by automatically converting the blanks successively severed from the end of the sheet or strip of paper, or other sheet material, into receptacles of the desired character.

Generally stated, the object of the invention is to provide a novel and improved construction of automatic machine for feeding and blanking the sheet material, and for converting the blanks into receptacles of the desired character, in a more satisfactory and better manner than heretofore, and in a manner tending to reduce the cost of production of butter dishes or similar receptacles, and at the same time insure greater accuracy and certainty in the work of converting the sheet material into receptacles of this kind.

It is also an object to provide certain details and features of construction and novel combinations tending to increase the general efficiency and the desirability of an automatic machine for blanking and forming butter dishes, or other similar receptacles of this particular character, as will hereinafter more fully appear.

It is also an object to provide an improved structure and arrangement whereby the cost of building and constructing a machine of this kind will be materially reduced, and tending to reduce the upkeep or running expenses of the machine as well.

To the foregoing and other useful ends, the invention consists in the matters hereinafter set forth and claimed, and shown in the accompanying drawings, in which—

Fig. 1 is a side elevation of an automatic printing and blanking and dish-forming machine embodying the principles of the invention.

Fig. 2 is a longitudinal section of said machine.

Fig. 3 is a side elevation of the other side of said machine, with certain portions broken away, and with certain portions in longitudinal section, for convenience of illustration.

Fig. 4 is an enlarged, horizontal section showing a portion of the machine, the section being taken on line 4—4 in Fig. 1.

Fig. 5 is an enlarged, vertical section of the right-hand end portion of the machine shown in Fig. 1, taken on a different line from the line on which the section is taken in Fig. 2.

Fig. 6 is a vertical section on line 6—6 in Fig. 5.

Fig. 7 is a plan of one of the blanks from which the butter dishes are made.

Fig. 8 is a perspective view of one of said blanks in partially folded condition.

Fig. 9 is a perspective of one of the completed butter dishes, showing the same folded and creased and stapled at the ends thereof.

As thus illustrated and referring to Figs. 7, 8 and 9, the dish to be made is of the kind ordinarily known as a creased dish for use in selling butter or similar commodities. The blank shown in Fig. 7 comprises an oblong, rectangular bottom section 1, side sections 2, upwardly tapered end sections 3, corner sections 4, and triangular sections 5, these sections being separated from each other by means of score lines or crease lines 6, 7, 8 and 9 formed by scoring or creasing the paper or other sheet material in the desired manner. The blanks are cut off at the corners, as shown at 10, to facilitate the folding and stapling operations, and after the blank has been formed and has been cut off from the sheet or strip of paper or other sheet material, in the form shown in Fig. 7, the folding operation shown in Fig. 8 is then accomplished, so that the upwardly tapered sections 3 are bent downwardly and inwardly toward each other, and so that the side walls 2 are also bent downwardly and inwardly toward each other. At the same time the sections 4 and 5 are bent around as shown, so that the sections 4 are superposed on the sections 5, while the latter are superposed upon the sections 3 which form the upwardly tapered and creased end walls of the dish, when the dish is finished. When

the two-ply or double-thickness flaps formed by the sections 4 and 5 have been folded around in proper position, wide staples 11 are then inserted from the outside, as shown

in Fig. 9, across the meeting points of the two-ply flaps produced at the opposite ends of the dish, and through the upwardly tapered walls 3 of the dish, so that each lug of 5 each staple is inserted through three thicknesses of the paper or other sheet material, and then clinched on the inner surface of the dish, as shown in Fig. 9 of the drawings. Thus the bottom 1 of the dish is rectangular, 10 and also, the top of the dish is rectangular, and the blank is so cut and folded that the downwardly tapered side walls 2 have the same slant or angle or inclination that the end walls of the dish have. Each side wall 15 2 comprises only a single thickness, while each complete end wall of the dish is made up of single thicknesses at some places, and three thicknesses at other places, in the manner shown and described. The two-ply flaps 20 formed by the sections 5, and by portions of the sections 4, do not overlap each other, but merely meet at their points, or at the points formed at the corners 12 of the blank, as shown. Thus a dish is formed with square 25 corners, but without any cracks or seams through which the contents of the dish could leak or escape, inasmuch as the creases formed at 13 inside of the dish, and the creases 14 formed outside of the dish, are not open cuts made by cutting through the paper or other sheet material but are merely rounded edges formed by scoring the sheet material along these lines, and by then folding the material upon itself, thus forming a 30 tight and non-leaking dish.

The machine for making the blanks, and for automatically feeding the sheet material and blanks and converting the blanks into dishes, comprises, preferably, a printing press 15 of any suitable or desired character, having rolls 16 and 17, for feeding and printing the paper in the desired manner. Said rolls, and the inking rolls 18, are operated by the gears 19, through which these 40 different rolls are interconnected. The entire train of gearing is driven by a gear 20, which latter is in turn suitably driven, as will hereinafter more fully appear. Said printing press feeds the sheet or strip of paper continuously, and prints any desired ornamentation or advertising or information on the outer surface of the sheet of paper to be converted into dishes.

From the printing press the sheet of paper 45 passes between the rolls 22 and 23, the upper roll 22 being hollow and having a steam pipe 24 to heat the roll to dry the ink on the upper surface of the sheet or strip of paper. The lower roll 23 is arranged in a receptacle 50 which contains the paraffin 26 for paraffining the under surface of the sheet, so that the inner surface of each dish will be paraffined in the desired manner. This receptacle has a chamber 27 in the bottom thereof, and 55 steam can be admitted to this chamber by a

pipe 28, thereby to keep the paraffin in melted condition. Excess of paraffin on the roll 23 is avoided or controlled by the element 29 which rubs against this roll, and which can be moved toward or away from the roll by the adjusting screw 30 thereby to insure the right quantity of paraffin on the roll for the required work. Rolls 22 and 23 feed the paper at the same speed that the sheet or strip is fed by the rolls 16 and 17 of 75 the printing press when the roll 23 is on the axis member or shaft 31 of the gear 32 which engages the gear 20 previously mentioned. The pressure of the upper roll 22 upon the paper resting on the lower roll 23 is controlled or regulated by set screws 33, the ends of the roll 22 being supported in blocks 34 that slide up and down in guides 35, in a manner that will be readily understood.

The sheet or strip of paper is then fed 85 between the feed rolls 341 and 351, the upper roll being supported by blocks 36 at the sides of the machine, which blocks 36 are suitably mounted to slide up and down, so that the roll 341 is moved up and down relative to the lower roll 351 with which it co-operates to feed the sheet or strip of paper. A table 37 is provided between the rolls 22, 23 and the rolls 341, 351, for the strip or sheet of paper to rest upon. The roll 351 is mounted 90 on the shaft 38 of the sprocket wheel 39, and this sprocket wheel is connected by a chain 40 with the sprocket 41 on the shaft 31 previously mentioned, whereby the roll 351 is driven at higher speed than the roll 23, for 95 a purpose which will hereinafter more fully appear.

The main drive shaft of the machine is the shaft 42, which is mounted in suitable bearings, and is connected by gears 43, 44, 105 45, 46, 47 and 48 with the gear 32 previously mentioned, whereby the various printing-press rolls and feeding rolls are all driven at the proper or desired speeds.

After passing through the printing press, 110 and after passing between the rolls for feeding the sheet or strip, the latter then passes through the blanking machine, which latter comprises the upper and lower dies 49 and 50 between which the paper or sheet of material must pass in order to be blanked out in the manner shown in Fig. 7 of the drawings. The lower die 50 is carried by the body frame 51 of the machine, while the upper die 49 is carried by the vertically 115 movable head 52, which latter has downwardly extending side portions 53 which engage the eccentric cam devices 64 on the opposite ends of the shaft 42 previously mentioned, whereby the head 52 is reciprocated 120 up and down in the desired manner, and in properly timed relation to the other elements of the machine as a whole. The upper die is provided with creasing knives or blades 55, 125 of any suitable character, arranged to form 130

the crease lines shown on the blank illustrated in Fig. 7 of the drawings, so that the blank may be folded along these lines, as previously explained. These creasing knives or blades co-operate with the lower die 50, which latter has the parallel grooves 56 for making the crease lines 6 previously mentioned, on the blank, and the lower die also has the grooves 57 for forming the crease lines 7 previously mentioned, and has grooves 58 for forming the crease lines 8 previously mentioned. The grooves 59 are for forming the crease lines 9 previously mentioned, and it will be understood that the grooves thus formed in the lower die receive the knives or blades of the upper die, thus creasing the blank in the desired manner. At one side, the upper die has the cutting knife 60 which co-operates with the stationary knife 61 on the lower die to cut off the end blank of the strip along the lines or edges 62 of the blanks, and it will be understood that the two dies are provided with means for forming the notches in the parallel edges of the sheet or strip of paper, which notches form the beveled or angled portions 10 of the blanks. It will be seen that these V-shaped notches are cut in the edges of the sheet or strip of paper, opposite each other, and that the severing lines predetermined for the blanks intersect the inner ends or points of these notches, so that each blank when cut off is of the shape shown in Fig. 7. Thus the edges 62 of the blank form the upper side edges of the finished dish, while the edges 10 form the upper edges of the end walls of the dish, in conjunction with the edges 63 of the upwardly-tapered end walls previously mentioned. The head which carries the upper die of the blanking press is also provided with spring-pressed members 64 adapted to yieldingly engage the sheet of paper or other sheet material, just ahead of the blanking operation, in order to make sure that the paper will be held stationary during the blanking operation. The upper head of the blanking machine is also provided with a spring-pressed rod 65 for marking the blanks. The rod 65 is preferably operated by a cam 66 on the shaft 67, which latter is automatically operated by a link 68 pivoted at 69 on a stationary portion of the machine, at its lower end, and pivoted at 70 to the upper end of the arm 71 which is loose on said shaft 67, but connected thereto by a ratchet device 710, whereby this shaft is automatically actuated by the up and down movement of the upper head of the blanking machine. Therefore, the cam 66 is so formed, and is so timed in its intermittent rotation, that the rod 65 is pushed downward at the right time by the cam projection 660, to mark every fiftieth blank, for example, so that by counting the marked dishes the total number made can be estimated readily. For

this purpose the ratchet 710 will have fifty teeth, but any other number may be used. The spring 72 is applied to the rod 65 to keep the latter normally raised, so that the upper end of this rod will always bear 71 against the cam 66, whereby the rod is reciprocated vertically in the desired manner. The side portions 53 slide up and down in guides 74 provided on the stationary body frame. Levers 75 are pivoted at 76 on the sides of the body frame, and have their shorter ends connected by links 77 with the previously mentioned supports 36 for the upper roll 341, and tappets 78 are provided on the vertically reciprocating side portions 80 53 to engage the set screws 79 on the longer ends of these levers, whereby the upper feed roll is automatically lifted by the downward movement of the upper head of the blanking press, in such a manner that the rolls 341 85 and 351 are rendered inoperative to feed the paper during the blanking operation.

From the blanking press the sheet or strip of paper passes on to the dish-forming machine, or machine for forming receptacles 90 of any suitable character, comprising the vertically reciprocating member 80 upon the upper end of which the oblong or rectangular block or form 81 is mounted. The member 80 slides up and down in the stationary 95 guideway 82 suitably formed in the body frame of the machine. At the time that the end blank is cut off by the knife 60, the form 81 is in a partially raised position, and is in a position to receive the said end blank, 100 so that when cut off the blank rests upon the flat top of this form 81, with the sections 3 of the blank in engagement with the under sides of the upturned end portions of the stationary folding fingers 83, shown in 105 Figs. 5 and 6 of the drawings. When the plunger head or form 81 then moves upward, the side portions 2 of the blank strike the stationary walls 84 of the folding means, whereby the upward movement of the plunger 110 head 81 raises the bottom section 1 of the blank, but causes the sections 2 and 3 to be deflected downward. The further upward movement of the form or plunger head 81 brings the sections 4 and 5 around into 115 the position shown in Fig. 8, and the creased edges 14 then strike the inwardly inclined surfaces 85 of the stapler heads 86, which latter may be of any suitable known or approved form, and which are preferably arranged horizontally in position to insert the staples 11 previously mentioned. During such insertion, of course, the folded and doubled end portions of the dish are pressed against the vertically disposed and flat end surfaces 87 of the plunger head or form 81 120 previously mentioned. In this way the staplers are advantageously arranged horizontally in opposed relation to each other, and in such a manner that the staple form- 125 130

ers and drivers (not shown), of any suitable character, are actuated horizontally to compress the end portions of the dish and to then insert the two staples in the desired manner. The member 80 is operated up and down by the eccentric cam device 88 on the shaft 42, in the manner shown in Figs. 2, 3 and 5, through the medium of the arm 89 and the link 90, in a manner that will be readily understood, the other end of the eccentric strap being connected by a link 91 with the stationary body frame, so that the link 90 is reciprocated up and down to reciprocate the plunger head 81 in properly timed relation to the other elements. Wire 92 is fed to the staplers, by feed devices 93, of any suitable character, operated by the rods 94 connected at their lower ends to the levers 95, which latter are pivoted at 96 upon a stationary portion of the machine. These levers 95 have rollers 97 to engage the cams 98, whereby the rods 94 are reciprocated vertically, thus causing the ratchet mechanism 99 of said feed devices to intermittently feed the wire in the manner commonly employed in stapling machines, whereby the wire is supplied by which the staples are made. Upwardly extending fingers 100 keep the end walls of the completed dishes pressed inward, somewhat, and cause these end walls to slide upwardly over the hooks 101, which are mounted on the lower end portions of the vertically reciprocating members 102, which latter are connected by links 103 to the distal ends of the swinging arms 104 suitably pivoted at 105 on stationary portions of the machine. A rod 106 connects one arm 104 with the actuating arm 107 below, which arm 107 has a roller 108 to engage the cam 109 on the shaft 42 previously mentioned. A spring 110 connects the lower end of the rod 106 with a stationary portion of the machine, so that the roller 108 is maintained in engagement with its allotted cam. The two arms 104 are rigid with the rock shaft 105, so that actuation of one arm causes the actuation of all of the hooks 101 previously mentioned. At the proper time therefore, insured by a proper timing of the different operative elements of the machine, the hooks 101 engage the lower edges of the end walls of the finished dish on the plunger head 81, and the plunger head then moves downward and the hooks 101 move upward, thus in effect lifting the finished dishes from the reciprocating plunger head. The dishes thus made upside down are caused to nest or stack in the guides 111, and the guides are so formed that the stack moves upwardly and then horizontally, so that the dishes at the upper end of the stack fall off and are received in any suitable manner. For the actuation of the staplers the outer, horizontally reciprocating heads 112 of the staplers are con-

nected by links 113 with the upper ends of the lever arms 114, and the latter are pivoted at 115 on stationary portions of the machine. The lower ends of these levers 114 have engaging portions 116 for engaging the cam grooves 117 in the cam devices 118 on the outer ends of the shaft 42 previously mentioned. Thus the levers 114 are vibrated about their axes 115, in a common inclined plane, the cam grooves 117 being properly shaped for this purpose, whereby the stapler heads 112 are reciprocated toward and away from each other in a common horizontal plane. Thus the staples are driven in a common horizontal plane, but it will be seen that nevertheless the end walls of the dish, like the side walls, are flared or inclined outwardly. This is accomplished, as shown and described, by providing the plunger head 81 with flat and vertically disposed end surfaces, as stated, against which the flexible end portions of the dish can be pressed by the horizontally disposed staplers, in order that the inner ends or points of the staples may be clinched against the ends of the plunger head 87, in a manner that will be readily understood. Thus the staple formers (not shown) of the staplers move the end walls of the dish a distance before compressing the creased and doubled portions against the ends of the plunger head. This, as shown and described, is in order that the staplers may be arranged horizontally, in a common horizontal plane, which is advantageous in various ways. The opposing ends of the stationary stapler heads 86 are formed, as shown in Fig. 6, to co-operate in the folding of the blank, in the manner previously explained.

Thus each time the plunger head 81 moves upward a dish is formed and stapled, and during such time the blanking press is forming another blank; and, during this time, the printing press and the rolls 22 and 23 are operating to continuously feed the paper, but the paper thus fed will simply buckle upwardly, in front of the blanking press, and this slack in the paper will then be taken up quickly as soon as the upper head of the blanking press moves upward, and as soon as the feed rolls 341 and 351 again resume their function of feeding the paper. This, as previously explained, is because of the fact that the roll 341 works at a higher speed than the rolls of the printing press, and, consequently, the accumulation of paper formed between the printing press and the blanking press, during the operation of simultaneously forming a blank while a previously formed blank is being converted into a dish, will be quickly fed forward in the desired manner as soon as the blanking operation and the dish-forming operation are completed. Therefore, each time the paper is moved forward in the blanking press the

end blank is brought into proper position in the dish-forming machine, directly above the plunger head 81, and then when the blanking press is operating the knife 60 cuts off this end blank, and at the same time forms another blank on the end of the sheet or strip. Simultaneously therewith, the plunger 81 is moving upward to form the cut-off blank into a dish. The stapling operation, therefore, is performed by the driving of the staples in a common horizontal plane, which plane is a distance above the plane in which the blanking operation is accomplished, said blanking operation being performed in the common plane of feeding and printing the paper. The form or plunger head 81 does not tightly fit the dish when the latter is finished, and the dish is easily stripped or detached from the plunger head 81 by the hooks 101 in the manner previously explained.

The main driving shaft 119 is mounted in suitable bearings on the body frame, and is provided with a pinion 120 for engagement with the gear wheel 121 mounted on the shaft 42 previously mentioned. The shaft 119 can be driven in any suitable or desired manner, and through the gearing 120 and 121 will rotate the shaft 42 and thereby operate the printing press and the feeding rolls and the blanking press and the dish-forming machine, through the power-transmitting connections previously described.

Thus the paper is automatically printed and blanked and formed into receptacles each having upwardly tapered, creased end walls, upon the inner surface of each end of the dish, and having inclined side walls and end walls disposed at right angles to each other to provide square corners for the top of the dish. In the stapling operation, as explained, the end portions of the dish are pressed inward and caused to assume vertical positions in order to compress the creased and doubled portions of the sheet material against the ends of the plunger head 81, and in order to clinch the staples in the manner explained, but the ends of the dish tend to spring outward when released by the stapling mechanism, so that the end walls of the dish are practically inclined at the same angle that the sides 2 are when the dish is finished. In practice, of course, the upper edges 62 of the sides will tend to curve or bow outwardly a little, perhaps, because of the more or less resilient quality of the sheet material, and the tendency resulting from the folding of the sheet materials along the lines 8 previously mentioned. However, the pressing of the end portions of the dish inwardly until they bear against the ends of the plunger head 81, tends to bend the material a little more sharply along the lines 8, and the corners thus formed by the lines 8, when the dish

is viewed from above, are square corners, or approximately so, in the making of the dishes by the machinery and method shown and described. When the walls 3 are pressed inward, during the fastening operation, they are substantially upright and parallel, as they will be pressed flatwise against the opposite ends of the plunger head 81, and the two-ply flaps formed by the sections 4 and 5 will then be stapled to these upwardly tapered walls 3, and by this it is meant that these walls taper upwardly when the dish is right-side up, as shown in Fig. 9 of the drawings. Thus the two-ply flaps, when the receptacle is finished, occupy inclined planes at opposite sides of the dish, and the square corners of the dish are located in these planes. The receptacle has four sides, of course, inasmuch as the sections 3, 4 and 5 form the end walls of the oblong receptacle, but these end walls are at opposite sides of the receptacle, and form side walls, which are narrower than the longer side walls 2 which extend longitudinally of the oblong receptacle.

It will be seen that guide plates 122 are provided on rods 123, these plates being disposed in position to engage the side edges of the sheet or strip of paper. The rods 123 are endwise adjustable, being mounted in the body frame for this purpose, so that the guide plates 122 can be moved toward and away from each other to adjust them relatively to the sheet or strip of paper.

As a matter of still further improvement, it will be seen that the elements 124, shown more clearly in Fig. 6, are disposed above the hooks or engaging portions 101, and are rigid therewith, being rigidly united to the vertically reciprocating members 102 previously described. Thus, while the hooks 101 are engaging the edges of the lowermost dish or receptacle, the portions 124 are at the same time engaging the lower edges of a dish above, so that the stack of dishes is given suitable support at the lower end thereof. In addition, the portions 125, shown more clearly in Fig. 5, are in position to receive the lower edges 62 of the walls 2 of the receptacle, when the latter is lifted upwardly by the hooks 101, whereby the entire stack of nested dishes is supported on these portions 125 when the hooks 101 and the engaging elements 124 move downwardly to engage the lowermost receptacle to take a fresh grip on the lower portion of the stack. As soon as the dishes are successively raised above the upstanding portions 100, the creased and folded opposite sides of the receptacles are free to spring outward, so that each receptacle ultimately springs outwardly at its ends upon the tops of the engaging elements 124, and above these elements 124 the walls of the receptacles assume the normal positions, substantially so, which

they occupy in the ultimate product, or in the finished receptacle. Of course, the lower surface of the sheet or strip is paraffined, by the roll 23, as previously explained, and it is this paraffined surface of the sheet material which is presented to the four flat sides of the plunger head 81, which latter is rectangular and formed with parallel flat sides. However, inasmuch as this rectangular plunger head does not fit the interior of the receptacle, the receptacle being of a different shape, it follows that the paraffined inner surface of the receptacle does not come in contact with the sides of the plunger head, except where the stapling operations are performed, and in this way the paraffined interior of the receptacle does not adhere to the plunger head, to any great extent, and hence the stripping or detaching of the finished receptacle from the plunger head is easily accomplished.

What I claim as my invention is:

1. The method of making a receptacle from sheet material, comprising the blanking of the sheet material in the desired manner, preparatory to the folding thereof, thereafter folding the sheet material along predetermined lines formed on the blank, thereby forming overlapping portions at opposite sides of the receptacle, so that a substantially rectangular receptacle will be formed with four outwardly inclined sides, temporarily pressing inwardly the two opposite sides having said overlapping portions, so that the middle portions of these two sides are substantially upright and parallel during the fastening operation, and thereafter releasing the receptacle and allowing said inwardly pressed sides to spring outward.

2. A method as specified in claim 1, said middle portions of the two opposite sides which are pressed inwardly being in the form of upwardly tapered and creased inner end walls for the receptacle, whereby the blank is folded in a manner to prevent cracks or openings through which leakage of the contents of the receptacle could occur.

3. A method as specified in claim 1, said blanking operation comprising the forming of tapered sections foldably connected with other portions of the blank, and said folding operation producing two-ply creased flaps which are folded against the outer sides of said tapered sections, and said fastening operation comprising the insertion of a single staple through each tapered section to fasten said flaps thereto.

4. A method as specified in claim 1, said blanking and folding operations co-operating to produce two-ply creased flaps forming certain of said overlapping portions, in a manner to prevent any flap from overlapping another flap, with all of said flaps on the outer surface of the receptacle, and with

upwardly tapered walls having creased edges, said flaps being secured to said upwardly tapered walls.

5. The method of making receptacles, comprising the blanking of sheet material to form a blank having predetermined fold lines thereon, folding the blank thus made, thereby producing upwardly tapered inside walls having creased edges, as well as outside two-ply flaps having blunt ends forming meeting points a distance below the upper edge of the receptacle, and also substantially square corners for the top of the receptacle, and fastening the two-ply flaps to the upwardly tapered walls, comprising the pressing of said tapered walls inwardly, so that these tapered walls are substantially at right angles to the bottom of the receptacle during the fastening operation, and thereafter allowing these walls to spring outward.

6. A method as specified in claim 1, comprising the intermittent feeding of sheet material to form successive blanks therefrom, and using the feeding motion to feed each blank into position to be folded in the manner stated.

7. The method of making receptacles, comprising the blanking of sheet material to form a blank that can be folded in the desired manner, folding the blank to provide sides for the receptacle, pressing inwardly one or more sides beyond the normal position thereof in the ultimate product, performing a fastening operation on the material thus pressed beyond its ultimate position in the finished receptacle, and thereafter allowing the inwardly pressed material to spring outward to assume the normal position thereof.

8. In a machine for making receptacles, the combination of a printing press for printing and feeding sheet material, drying and paraffining rolls to feed the sheet material from the printing press, comprising a heated roll and a paraffining roll between which the paper is fed, and instrumentalities for thereafter blanking the sheet material, and for ultimately and successively folding the blanks, and for fastening the blanks in folded position, thereby to produce receptacles which are printed and dried on the outside, and which have a paraffined interior surface.

9. In a machine for making receptacles, the combination of blanking press means to form transverse fold lines between said parallel lines, forming the rectangular bottom of the receptacle, means to form outwardly converging fold lines leading from the corners formed between said parallel lines and said transverse lines, outside of said transverse lines and between said parallel lines, means to form outwardly divergent fold lines leading from the ends of said transverse lines, outside of said parallel lines, and

- means to form oblique edges for the four corners of the blank, forming four obtuse corners in which said outwardly divergent lines terminate, whereby to produce blanks 5 which are foldable into receptacles having rectangular bottoms, and having substantially rectangular tops, said oblique edges forming horizontal edges for the top of each receptacle, in combination with instrumentalities for successively folding the blanks into receptacles each having outwardly inclined side walls, said instrumentalities comprising means for pressing two opposite walls of the receptacle inwardly beyond 10 their normal positions in the finished receptacle, in combination with means for inserting staples through the portions thus temporarily pressed toward each other, thereby to fasten the blank in folded condition, 15 whereby the sections between said outwardly convergent lines form upwardly tapered walls at two opposite sides of the receptacle.
10. In a machine for making receptacles, having outwardly inclined side walls, instrumentalities for successively folding the blanks, and for stapling the blanks in folded condition, including means to press two opposite sides of each receptacle inwardly and toward each other beyond the normal positions of these sides in the finished receptacle, thereby to temporarily hold these opposite sides in position to receive the fastening staples.
11. A structure as specified in claim 10, 25 said instrumentalities comprising two oppositely arranged stationary elements for engaging opposite edge portions of the blank, and inclined stationary portions to engage other edge portions of the blank, 30 said first mentioned elements being disposed in position to cause said abnormal deflection of two opposite sides of the receptacle toward each other, said instrumentalities also comprising a plunger adapted to co-operate 35 with said elements to fold the blanks, said plunger having flat and substantially parallel side surfaces to receive said abnormally deflected side portions of the receptacle, upon which these portions are 40 compressed to perform the stapling operation thereon.
12. A structure as specified in claim 10, 45 said instrumentalities comprising a plunger head upon which the blanks are successively folded, said head having parallel outer surfaces to receive said abnormally deflected portions of the receptacle, upon which these portions are compressed to perform the 50 stapling operation thereon.
13. A structure as specified in claim 10, 55 said instrumentalities being operative to fold each blank to produce non-overlapping two-ply flaps at opposite sides of each receptacle, and having means to insert staples 60 through said flaps, and through the up- wardly tapered inner walls formed by the sections of sheet material between said outwardly convergent lines.
14. A structure as specified in claim 10, 65 said instrumentalities comprising stationary elements and movable means co-operating therewith to form each receptacle upside down, in combination with means for receiving each receptacle and nesting the receptacles together to form a stack.
15. A structure as specified in claim 10, 70 said instrumentalities comprising oppositely arranged staplers disposed in position to operate in a common horizontal plane, and comprising a vertically reciprocating plunger head upon which the stapling operations are performed.
16. A structure as specified in claim 10, 75 comprising staplers arranged opposite each other to operate in a common horizontal plane, a shaft, cams on said shaft, levers having means for engaging said cams, and means for connecting said levers to actuate said staplers, whereby rotation of said shaft causes the simultaneous actuation of said 80 staplers toward and away from each other in the said common plane thereof, in combination with a vertically reciprocating plunger head to support the blank during 85 the folding thereof, having opposite parallel sides upon which the stapling operations are performed.
17. In a machine for making receptacles, the combination of a reciprocating plunger 90 head upon which to perform the operation of folding a blank to convert the same into a receptacle, instrumentalities to co-operate with said plunger head to fold the blank in a manner to produce a receptacle having outwardly inclined sides, and oppositely arranged 95 staplers disposed in position to operate at right angles to the reciprocating motion of said plunger head, and in position to insert staples through opposite sides of the receptacle, against opposite sides of said plunger head, in a manner to temporarily 100 press the opposite sides of the receptacle toward each other, beyond the positions which they occupy in the finished receptacle.
18. A structure as specified in claim 17, 105 said instrumentalities being adapted to fold the blank in a manner to produce upwardly tapered inner walls at opposite sides of the receptacle, and two-ply outer flaps, said 110 staplers being operative to insert staples through said flaps and upwardly tapered walls, in such a manner that the two opposite sides thus stapled will spring outward after being released by the machine.
19. A structure as specified in claim 17, 115 said instrumentalities being operative to fold the blank to produce a receptacle having a rectangular bottom, and a substantially rectangular top, with non-overlapping two-ply 120 flaps at opposite sides of the receptacle, said 125 flaps at opposite sides of the receptacle, said 130

staplers being operative to insert the staples through said flaps.

20. In a machine for making receptacles, of predetermined form and shape from blanks, folding instrumentalities comprising a plunger head of different shape, whereby said plunger head does not fit the interior of the finished receptacle, and including means co-operating with said plunger head to fold the blank thereon, and to press certain portions thereof inwardly beyond the normal positions thereof in the finished receptacle, for the purpose of performing fastening operations thereon.

15 21. A structure as specified in claim 20, said plunger head being rectangular and having parallel flat sides, and said receptacle having outwardly inclined sides.

22. A structure as specified in claim 20, 20 said plunger head having parallel flat opposite sides to receive certain portions of the receptacle, and said instrumentalities comprising stapling mechanism operating at right angles to the motion of said plunger 25 head, adapted to insert staples through the receptacle against said opposite sides of the plunger head.

23. A structure as specified in claim 20, 30 said instrumentalities comprising staplers for inserting staples in the folded blank, said staplers having stationary and beveled or inclined ends adjacent said plunger head, thereby to deflect and fold certain portions of the blank in the desired manner.

35 24. In a machine for making receptacles, the combination of a printing press for printing and feeding a sheet or strip of paper, rolls to receive the sheet or strip from the printing press, power transmitting connections for operating one of said rolls, a 40 feeding device to intermittently feed the sheet or strip of paper, arranged to receive the sheet or strip from said rolls, means on the axis of said driven roll and whereby the rotation of said driven roll operates said feeding device, and instrumentalities for receiving the sheet or strip from said feeding device, operative without stopping said printing press, for blanking the sheet material and successively converting the blanks into receptacles.

45 25. A structure as specified in claim 24, said driven roll being equipped with means for applying paraffin to the under side of the sheet or strip of paper.

50 26. A structure as specified in claim 24, one of said rolls being heated to dry the ink applied to the sheet or strip by said printing press, the heated roll pressing the paper against the driven roll.

55 27. A structure as specified in claim 24, said feeding device comprising continuously driven feed rolls, and means for intermittently causing separation of said rolls to 60 intermittently stop the feeding of the sheet

to said blanking means and to said instrumentalities.

28. A structure as specified in claim 24, in combination with gearing on the axis of said driven roll whereby operation of said driven roll operates said printing press.

29. A structure as specified in claim 24, in combination with means whereby a portion of said power transmitting means in the form of a driven shaft is operative to transmit power to operate said blanking and receptacle forming instrumentalities in sequential timed relation and whereby the entire machine is driven by this one shaft.

30. In a machine for making receptacles, the combination of instrumentalities for folding and fastening the blanks to produce the desired receptacles, so that the receptacles are formed upside down and accumulated in a stack, engaging portions to engage the lower edges of each receptacle, to release the receptacle from the forming instrumentalities, means for lifting the receptacle and those on top thereof to a higher position, means for supporting the lower receptacle and those supported thereon in said elevated position, elements rigid with said portions and disposed above in position to successively engage the lower edges of the receptacles, and means for vertically reciprocating said elements and engaging portions, said supporting means holding the stack against downward movement when said elements and engaging portions move downward.

100 31. In a machine for making receptacles, the combination of a blanking press for blanking the sheet material to form blanks, instrumentalities for successively converting the blanks into receptacles, feeding means serving to feed the sheet to said blanking press and also to said instrumentalities, in combination with guide plates disposed in position to engage the edges of the sheet or strip, with their straight lower edges on the blanking press, thereby to properly guide the sheet or strip through the blanking press and toward and into said instrumentalities, and transverse rods upon the inner ends of which said plates are mounted in fixed position to engage the side edges of the sheet or strip, and supporting means on which said rods are endwise adjustable to properly adjust the guide plates relatively to the sheet or strip of paper.

105 32. In a machine for making receptacles, the combination of a printing press, rolls to feed the sheet or strip of paper therefrom, a feeding device to receive the sheet or strip from said rolls, a blanking press for forming the blanks from which the receptacles are made, adapted to form each blank with a rectangular bottom section, means for successively converting the blanks into

receptacles, utilizing the said feeding device to feed the end blank into position for folding, thereby obviating the necessity of blank feeding means between the blanking press and the folding means, means on the blanking press for cutting off the end blank parallel with its rectangular bottom section, after the blank is in position for folding, spring-pressed means to bear upon the sheet 5 and stop its feeding motion during the operation of the blanking press, and automatic means to control said feeding device to cause a cessation of the feeding action there- 10 of while said spring-pressed means are bearing against the sheet or strip of paper, whereby the sheet or strip will buckle upwardly between said rolls and said feeding device, in combination with means for operating said feeding device at a higher speed 15 to take up the slack in the sheet or strip, 20

between said rolls and the feeding device, thereby to quickly feed the sheet or strip the desired distance after each blanking operation.

33. In a machine for making receptacles, 25 the combination with means for automatically paraffining the sheet or strip of paper on one side thereof, instrumentalities for automatically blanking the sheet material, and for converting the freshly paraffined blanks into receptacles, said instrumentalities comprising a plunger head shaped to occupy the interior of each receptacle, while the receptacle is being formed, but of a different shape from the interior of the finished receptacle, thereby to reduce the tendency of the paraffined interior of the receptacle to adhere to the plunger head. 30 35

EDWARD CRAIG.
